UNITED STATES PATENT OFFICE.

JOHN WHITE, OF HARTFORD, CONNECTICUT.

FIRE-ESCAPE.

SPECIFICATION forming part of Letters Patent No. 398,992, dated March 5, 1889.

Application filed May 16, 1888. Serial No. 274,113. (No model.)

To all whom it may concern:

Be it known that I, JOHN WHITE, of Hartford, in the county of Hartford and State of Connecticut, have invented certain new and useful Improvements in Fire-Escapes, of which the following is a full, clear, and exact description, whereby any one skilled in the art can make and use the same.

My invention relates to the class of apparatus that are adapted to be permanently attached to a building for the purpose of facilitating the escape of the occupants in case of fire; and my object is to provide an apparatus that shall be compact in form and so arranged as to be out of the way when not required for use, but capable of being instantly extended when there is any need of using it.

To this end my invention consists in a ladder-reel arranged on the inside of the wall of a house above the story to be protected by the escape, the wall being slotted for the extension of the ladder and provided with a guide-roller, in combination with the clamp and lever attachment with a pull-rope, by means of which the ladder can be extended; and it further consists in details of the apparatus and the combination of the parts, as more particularly hereinafter described, and pointed out in the claims.

Referring to the drawings, Figure 1 is a view in elevation of part of the front wall of a house, illustrating the application of my improvement. Fig. 2 is a view in vertical section of the wall, showing the location of the ladder-roll. Fig. 3 is a detail view of part of the ladder, showing the method of attaching the rungs. Fig. 4 is a detail front view of the balcony-floor. Fig. 5 is a detail plan view of a folding balcony or bracket, showing its socket in a slot below the window-sill and parts unfolded to steady the ladder.

In the accompanying drawings, the letter *a* denotes the front wall of a house; *b*, a window; *c*, the downwardly-sloping slot cut through the wall immediately under the roof *d*. In the line of the slot *c* and inside of the wall is mounted the ladder-reel *e*, on suitable bearings, in such position that the ladder *f*, the lower end of which lies on the guideway *g*, will, when the pressure of the clamp *h* is removed, slide through the slot and extend itself down-

ward in front of the window or tier of windows *b*. In order to wind the ladder up, a winch, *i*, connected by gearing to the spindle of the ladder-reel, is used, or other suitable means may be provided.

The clamp *h* consists, preferably, of a flexible band, *h*¹, embracing the drum *h*², and connected to the lever *h*³ on opposite sides of its pivot *h*⁴, the outer arm of the lever bearing a weight, *h*⁵, that clamps the reel firmly in its normal position and has to be lifted, as by means of the pull-rope *h*⁶, in order to allow the ladder to run out. The ladder *f* is made up, preferably, of the wire ropes *f*¹ and metallic rungs *f*², that have on their opposite ends the split clamping devices *f*³, that are tightened upon the ropes by means of clamp-screws.

The slot *c* is closed on the outside by a hinged plate, *c*¹, that carries a guide-roller, *c*², and is pushed outward by the weighted lower end of the ladder as soon as the hold of the brake or clamp is removed from the ladder-reel. This guide-roll holds the ladder at a proper distance from the face of the wall while it is extended, and after it has been wound in the plate may be closed to cover the opening.

Under each of the windows, in a slot, *j*, in the wall, is located a sectional bracket, *k*, that may be swung out horizontally after the ladder is extended, and projecting through the ladder serves to steady it as well as form a landing-platform. This bracket or folding balcony is preferably made in sections *k*¹ *k*², each swinging on a vertical pivot, *l* *l*¹, about which is coiled a spring, *m*, that tends to swing the respective sections outward as soon as the bolt *n* is withdrawn. This bolt *n* has a handle extending through the wall and located in a position easy of access within the room. As soon as released, the sections swing outward in opposite directions, and passing between the side parts of the extended ladder press against them and serve to steady the ladder, at the same time providing a standing-place outside of the window for persons passing from the room to the ladder. The bolt *n* may be arranged to operate automatically as soon as the ladder is extended, or by the ladder in extending.

I claim as my invention—

1. In a fire-escape, in combination with the wall having the ladder-slot, the ladder-reel provided with a brake normally holding the reel against rotation, the sectional bracket located in a socket below the window and through the wall and adapted to be swung outward on a horizontal plane and engage the ladder, and the pull-rope connected to the roll-brake, all substantially as described.
2. In a fire-escape, in combination with a

flexible ladder secured at its upper end to a wall, a folding bracket formed in two sections, each swinging on a pivot and pressed outward by a spring, and the bolt whereby the folding parts of the bracket are temporarily held within the bracket-socket, all substantially as described.

JOHN WHITE.
